UNITED STATES PATENT OFFICE.

GUSTAF H. CARLSON, OF LOWELL, MASSACHUSETTS.

SEESAW.

SPECIFICATION forming part of Letters Patent No. 594,856, dated December 7, 1897.

Application filed April 19, 1897. Serial No. 632,899. (No model.)

To all whom it may concern:

Be it known that I, GUSTAF H. CARLSON, a citizen of the United States, residing at Lowell, in the county of Middlesex and Commonwealth of Massachusetts, have invented a certain new and useful Improvement in Seesaws, of which the following is a specification.

My invention relates to seesaws; and it consists in the devices and combinations herein described and claimed.

The object of this invention is to enable the seesaw to be operated without the use of the operators' feet, to enable one person to use the device without another person to counterbalance his weight, and to enable persons of different weights to balance each other without adjustment of the fulcrums.

In the accompanying drawings on three sheets, Figure 1 is a side elevation of a seesaw embodying my improvement; Fig. 2, a vertical longitudinal central section of the same; Fig. 3, a plan of the same.

A is a base consisting of longitudinal sills a' , resting on blocks $a^2 a^3 a^4 a^5$ (which serve as feet) and supporting a horizontal cross-beam a^6 . Two parallel vertical posts $a^8 a^9$ are secured to the cross-beam a^6 and at their upper ends are connected by a horizontal tie-beam a^7 , which carries on its upper surface, midway between its ends, a vertical fulcrum-block a^{10} , having a vertical longitudinal slit a^{11} . The posts $a^8 a^9$ are stiffened by inclined braces $a^{12} a^{13} a^{14} a^{15}$, which connect them to the sills $a' a'$ in an obvious manner. Two equal parallel horizontal beams $a^{16} a^{17}$ are supported on the cross-beam a^6 at right angles thereto inside the posts $a^8 a^9$.

The above-described parts are rigidly secured in place and constitute the stationary frame of the machine, which frame supports the movable parts hereinafter described.

To the beams $a^{16} a^{17}$ are pivoted four nearly vertical vibrating standards $B B' B^2 B^3$, the lower end of each of said standards being pivoted at b to one of said beams near an end thereof.

To each standard $B B' B^2 B^3$ are pivoted at $c' c'$ two parallel bars $C C'$, arranged one above the other, the outer ends of two pairs of such bars being pivoted at $c^2 c^3$ to opposite sides of the seat-support $D D'$, each seat-support consisting of two parallel angle-pieces $d d'$,

each having a horizontal part d^2 to support a foot-rest E and a vertical part d^3 , on the top of which a seat F is supported. The seat F 55 may be provided with a cushion f and an upholstered back f' . The parts $d^2 d^3$ of the seat-supports are preferably connected by braces $d^4 d^5$.

The upper parallel bars $C C$ at each end 60 of the seesaw are connected in pairs by parallel ties $c^4 c^5$, there being two such ties to each pair of upper parallel bars, the inner ends of said upper parallel bars extending nearly to the posts $a^8 a^9$ and beyond the standards $B B' B^2 B^3$ and the ties c^5 being at or near the inner ends of said upper bars $C C$. On each of the ties $c^6 c^6$ is secured a fulcrum-piece $c^6 c^6$, to which is pivoted at g the lower end of a fulcrum-rod $G G$, the upper end of 70 said rod being pivoted at g' to a lever H , and the latter is pivoted at h in the fulcrum-block a^{10} on the tie-beam a^7 .

The lever H is preferably formed in the three parts, the end portions $h' h^2$ being pivoted to the middle part h^3 of said lever at h^4 h^5 and being vertically slotted at $h^6 h^7$ to receive said part h^3 to enable said end portions to be raised or lowered, as shown by dotted lines in Fig. 2, to enable a person the more 80 easily to step into the seesaw. The parts h^2 h^3 , when in use, are held rigidly in line with the middle part h^3 by pins $h^8 h^9$, passed transversely through the end parts and the middle part across the slots $h^6 h^7$.

Equalizing-bars $I I'$ are pivoted at their middle points on horizontal pivots $i i'$ on the posts $a^8 a^9$, and the ends of said bars $I I'$ are pivoted at $i^2 i^3$ to the upper parallel rods $C C$, between the ends of the latter, to prevent the 90 standards $B B' B^2 B^3$ from tipping over on their pivots, so that when either end of the lever H rises or falls the seat nearest said end of said lever moves in the opposite direction, and each operator by bearing down on his 95 end of the lever raises his own seat and depresses that of the other operator. The ends of the lever H are provided with horizontal cross-bars $h^{10} h^{11}$ or handles to be grasped by the operators.

In order that the difference in weight of the operators may not interfere with the operation of the machine, I use one or more spiral springs $J J'$, two being shown, which connect

the corresponding ends of the two equalizing-bars with tension-levers j, j' , each pivoted at one end on the post $a^8 a^9$ and at the other to a tension-rod $j^2 j^3$, each tension-rod having on 5 its under side notches or hooks $j^4 j^5$, which engage horizontal studs $j^6 j^7$, projecting from said posts, so that by drawing the tension-rods endwise (to the left in the drawings) the tension-levers are raised and the springs are 10 stretched, with a tendency to raise the adjacent seat and depress the other seat. The heavier person will occupy the seat nearest the springs.

By tightening the springs sufficiently a person 15 occupying the seat nearest the spring may operate the seesaw alone. It follows that the other seat, its parallel bars, connecting-rods, and one member of each of the 20 equalizing-bars (the parts to the left of the dotted line in Fig. 1) may be omitted when the device is to be used by only one person.

I claim as my invention—

1. The combination of the frame, vibrating standards, pivoted thereon, parallel bars, pivoted at their inner ends on said standards, a seat-frame, pivoted to said parallel bars and provided with a seat, equalizing-bars pivoted on said frame and at their ends pivoted to said parallel bars, an operating-lever, pivoted 25 on said frame and rods connecting said lever and said parallel bars.

2. The combination of the frame, vibrating

standards, pivoted thereon, parallel bars, pivoted at their inner ends on said standards, a seat-frame, pivoted to said parallel bars and 35 provided with a seat, equalizing-bars pivoted on said frame and at their ends pivoted to said parallel bars, an operating-lever, pivoted on said frame, rods connecting said lever and said parallel bars, and springs, to 40 raise said equalizing-bars.

3. The combination of the frame, vibrating standards, pivoted thereon, parallel bars, pivoted at their inner ends on said standards, a seat-frame, pivoted to said parallel bars and 45 provided with a seat, equalizing-bars pivoted on said frame and at their ends pivoted to said parallel bars, an operating-lever, pivoted to said frame, rods connecting said operating-lever and said parallel bars, a tension-lever, 50 pivoted on said frame, a spring, connecting said lever and one of said equalizing-bars, a tension-rod, pivoted to the free end of said tension-lever and having notches to engage a stud on said frame, and said stud, to vary the 55 tension of said spring.

In witness whereof I have signed this specification, in the presence of two attesting witnesses, this 17th day of March, A. D. 1897.

GUSTAF H. CARLSON.

Witnesses:

ALBERT M. MOORE,
JAMES JACQUES.
